UNITED STATES PATENT OFFICE.

EDMUND ECKART, OF NEW ROCHELLE, NEW YORK, ASSIGNOR TO GERST-
ENDORFER BROS., OF NEW YORK, N. Y., A CORPORATION OF NEW
YORK.

CAN.

No. 840,484.

Specification of Letters Patent.

Patented Jan. 8, 1907.

Application filed December 20, 1905. Serial No. 292,558.

To all whom it may concern:

Be it known that I, EDMUND ECKART, a citizen of the United States, and a resident of New Rochelle, Westchester county, and 5 State of New York, have invented certain new and useful Improvements in Cans, of which the following is a specification.

My invention relates to cans of the kind used for storing and shipping ingredients 10 which are intended to be mixed for use—as, for instance, paints—and has for its object to provide such cans with separable receptacles for containing each of the ingredients separated from each other and in proper proportion for admixture.

My invention will be fully described hereinafter and the features of novelty will be pointed out in the appended claims.

Reference is to be had to the accompanying drawings, in which—

Figure 1 is an elevation of my improved can. Fig. 2 is a sectional view thereof on line 2-2 of Fig. 3, and Fig. 3 is a plan view of said can.

A represents the can proper or body, which 25 may be of any suitable construction and which is intended to contain one of the ingredients B, in the present showing oil. This body A is provided at its top with an opening C, through which the contents are admitted, 30 which opening is arranged to be closed by a dished cover D. This cover D is forced into the opening C and is provided with a flange D', so that said cover may be pried off by inserting a suitable instrument under said 35 flange.

E is a secondary receptacle for containing another of the ingredients—as, for instance, powdered pigment—and may be made of pasteboard or other suitable material. This 40 receptacle E is provided with a flange E' at its top, which forms a central opening E² for the introduction of the contents. The receptacle E is adapted to be received in the dished cover D as shown, and is held in position in the following manner: A seal F, of paper or like material, is secured to the top of the receptacle E and serves to close the opening E². The flange E' serves to strengthen the upper edge of the receptacle E and prevents the seal F from being torn at the edge 45 and leaves the central portion of said seal free to be broken, as hereinafter more fully explained. The said seal is provided with strips F', which may form part thereof or

may be secured to said seal. These strips F' 55 are arranged to be secured to the side of the can A, as shown in Fig. 2, those portions of said strips F' which engage the can A being covered by the label G. This label G serves as an additional securing means for said strips. 60 It is to be understood that the can A and the secondary receptacle E contain the several ingredients in proper proportion for admixture. When it is desired, as in the present case, to use the paint, the strips F' are cut or 65 broken, thus separating the receptacle E from the can A, after which the cover of said can A is removed. The central portion of the seal F is then broken, and the contents of the receptacle E are mixed with the contents 70 of the can A, resulting in a paint or other product properly mixed for use. By having the several ingredients in separate receptacles the goods may be stored and retain their various properties for a much longer time 75 than if sold already mixed. By having the two receptacles connected the danger of misplacement or loss of the one or the other is also obviated, and by having the contents of said receptacles in proportion a proper admixture is also assured.

While I have described and shown my improved can in connection with paints, I wish it distinctly understood that the same may be used wherever it is desired to sell or store 85 a product which consists of more than one ingredient intended to be mixed for use.

Various modifications may be made without departing from the nature of my invention as defined in the claims.

I claim as my invention—

1. The combination with a receptacle having a recess in its top, of another receptacle seated in said recess and having an open top, a seal closing said open top and having securing members extending to the upper portion of the first-named receptacle and along the sides thereof, and fastening means covering said securing members and holding them to the lower receptacle.

2. The combination, with a receptacle having a recess in its top, of another receptacle seated in said recess, and having an open top, and a seal extending across the said open top to close it and provided with lateral continuations which form securing members extending to the top of the first-named receptacle.

3. The combination, with a receptacle having a recess in its top, of another receptacle seated in said recess and having an open top, a seal closing said open top and having 5 securing members extending to the upper portion of the first-named receptacle and along the sides thereof, and a label or strip for fastening said securing members to the sides of the lower receptacle.
- 10 4. The combination, with a receptacle having a recess in one of its end faces, of another receptacle one end of which is set in said recess while the other end is open and is provided with an inwardly-extending 15 flange at said opening, a seal covering said

opening and securing members extending from the seal to the first-named receptacle.

5. The combination of different-sized receptacles disposed end to end, the contacting end surfaces differing in size with securing 20 members extending outwardly from the free end surface of the smaller receptacle to the edge of the larger receptacle.

In testimony whereof I hereunto subscribe my name in the presence of two subscribing 25 witnesses.

EDMUND ECKART.
